TOY WITH WINDABLE HEAD FOR ROTATION

Samuel H. Rosenthal, New York, N. Y.

Application August 2, 1950, Serial No. 177,172

1 Claim. (Cl. 46—118)

1

This invention relates to toy animals or dolls and has particular reference to a toy of said character which is adapted to provide amusement by winding the head so as to tension the same to thereby effect free rotation thereof when released.

The invention also has for an object to provide a toy animal or doll in which the head is mounted for rotation with reference to the body thereof and which is tensioned by the winding of a spring for effecting free rotation of the head when the spring is released.

Still another object of the invention is to provide in a toy of said character a rotatable casing connecting the head to the body thereof and having a torsion spring arranged therein and adapted to be tensioned by the pulling of a cord wound on the casing so as to provide free rotation of the head when the cord is released.

Still another object of the invention is to provide a toy animal or doll having musical tines adapted to be actuated to emit a musical sound when the head is rotated by the spring.

With the foregoing and other objects in view, reference is now made to the following specification and accompanying drawings in which the preferred embodiment of the invention is illustrated.

In the drawings:

Fig. 1 is a perspective view of a toy animal having a windable head constructed in accordance with the invention.

Fig. 2 is a fragmentary vertical sectional view showing the structure connecting the head and body of the toy.

Fig. 3 is a sectional view taken approximately on line 3—3 of Fig. 2.

Fig. 4 is a fragmentary sectional view taken approximately on line 4—4 of Fig. 2.

Fig. 5 is a fragmentary sectional view showing one of the prongs for engagement with the musical tines.

Referring to the drawings by characters of reference, the toy animal or doll may be of any desired character and as illustrated, the same includes a body or torso 10, a head 11 and limbs 12 secured to the body or torso for relative movement.

The head 11 is connected with the body or torso for relative turning movement and for this purpose the head is mounted on a spool-like housing 13 journaled for rotation on a central stud 14 which extends downwardly therethrough and is affixed at its lower end to metallic plates 16 and 17 by means of upper and lower nuts 18 and 19 tightened against said plates respectively and

2

functioning to tightly secure the inturned end portion 20 of the outer casing 21 of the body or torso 10 between the metal plates 16 and 17.

The housing 13 includes upper and lower annular plates 22 and 23 and a peripheral wall 24 located between and secured to said upper and lower plates inwardly of the outer edge thereof so as to provide recesses 25 surrounding the peripheral wall 24 and said upper and lower plates 22 and 23 and the peripheral wall forming an annular cavity 26 surrounding the stud 14 in which cavity is located a torsion spring 27 secured at its inner end in a slot 28 in said stud and at its outer end secured to the peripheral wall 24 by a rivet 29.

As illustrated, the spring 27 is arranged for rotating the spool-like housing 13 in a counter-clockwise direction to thereby tighten the spring and for rotation in a clockwise direction for free rotation of the head when the spring is released. It is to be understood however, that the spring 27 may be arranged for free rotation of the head in any desired direction. A cord 30 is secured to the peripheral wall 24 at its inner end as at 31 and is adapted to be wound thereupon within the annular recess 25 so as to turn the housing 13 on the stud 14 by manually pulling the cord outwardly to thereby unwind the cord therefrom and to wind the spring whereby when the cord is released, the spring will function to rotate the head and to again wind the cord on the housing 13.

The outer periphery 32 of the lower plate 23 is downturned so as to provide a guide for training the cord 30 into the recess 25. The head 11 is secured to the upper plate 22 by a drawstring or wire 33 which is threaded through the in-turned lower end 34 of the outer casing 35 of the head with the drawstring or wire tightened to thereby secure the inturned end 34 against the peripheral wall 24.

The upper plate 16 is provided with a plurality of radially arranged musical tines 36 which are secured to the upper surface thereof by rivets 37. The said tines are offset upwardly as at 38 with the outer portions thereof arranged parallel with the upper plate 16 and overlying rectangular radially arranged openings 39. The tines are adapted to be engaged by a plurality of arcuately spaced prongs 40 which are struck from the body 50 of the lower plate 23 of the housing 13 with the lower ends 41 thereof being rounded so as to ride over and depress the tines 36 when the head 11 is rotated in either direction. As each tine 36 springs upwardly after being depressed by the prongs 40, the same will emit a musical sound.

3

The body, head and limbs of the toy animal or doll are filled with kapok 43 or other filling material so as to extend the outer casings thereof.

What is claimed is:

In a toy figure, a body having a head and a torso, superposed plate members secured to the upper end of said torso, a stud affixed to said plates and projecting upwardly therefrom, a housing mounted for rotation on said stud and to which housing the head is affixed for turning movement with the housing, a torsion spring located in said housing and affixed at its inner end to said stud and at the outer end to said housing, said housing having a peripheral wall and side walls extending outwardly beyond said peripheral wall to provide an annular peripheral recess, a cord affixed at one end to said housing and adapted to be wound on the peripheral wall within said recess for turning said housing to thereby tension said spring by the pulling of the cord outwardly so as to unwind the cord therefrom and to wind the spring whereby the spring

4

will function to rotate the head and to again wind the cord on the housing when the cord is released, said housing having depending projections and the uppermost of said plates having tines affixed thereto so as to project above the upper surface thereof and adapted to be engaged by said projections when the housing is rotated to thereby cause said tines to emit sound.
